UNITED STATES PATENT OFFICE.

CHARLES G. OTIS, OF BROOKLYN, NEW YORK.

HYDRAULIC MOTOR FOR ELEVATORS AND OTHER PURPOSES.

SPECIFICATION forming part of Letters Patent No. 355,658, dated January 4, 1887.

Application filed September 24, 1886. Serial No. 214,456. (No model.)

To all whom it may concern:

Be it known that I, CHARLES G. OTIS, a citizen of the United States, residing at Brooklyn, in the county of Kings and State of New York, have invented a new and useful Improvement in Hydraulic Motors for Elevators and other Purposes, of which the following is a specification.

This invention relates to an improvement in hydraulic motors for elevators and other purposes; and it consists in certain novel features of construction, fully pointed out in the following specification and claims, and illustrated in the accompanying drawings, in which—

15 Figure 1 represents a vertical cross-section on the line $x-x$, Fig. 2. Fig. 2 is a vertical longitudinal section on the line $y-y$, Fig. 1. Fig. 3 is a horizontal section on the line $z-z$, Fig. 2. Fig. 4 is a vertical section on the line $x'-x'$, Fig. 2. Figs. 5 and 6 are detailed views of the slide-valve. Fig. 7 is a diagram showing the application of my motor to an elevator. Figs. 8 and 9 are sectional elevations of a modification, and Fig. 10 a sectional elevation 25 showing the series of pistons secured to the rotating piston-wheel.

Similar letters indicate corresponding parts.

In the drawings the letters A A designate two standards, in which are firmly mounted 30 a series of annular cylinders, B, each of which is provided with a stationary abutment, C, which extends across said cylinder, between the water-passages a and b , Fig. 1, and abuts against the piston-wheel D, which fits closely 35 over the cylinders B. Into each of the cylinders is fitted a piston, E, projecting from the inner surface of the piston-wheel, which, when acted upon by the water entering either of the passages a or b , will cause said piston-wheel 40 to make part of a revolution around the stationary cylinders.

A slide-valve, F, is fitted into the center of the series of cylinders, and serves to control the passage of the water to and from the same 45 in such a way that its pressure may be brought to bear on one or more of the pistons E at will, so that either one or more of the cylinders may be operated, as the work required of the motor may make necessary.

50 G is the supply-pipe, through which the water enters the motor under sufficient pressure for the work required. H is the dis-

charge-pipe, through which the water passes as it leaves the machine. These pipes connect, respectively, with supply and discharge 55 passages c d , which open into the valve-chest I opposite each other, as seen in Fig. 3.

At one end of the slide-valve are formed two chambers, e and f , separated from each other by a partition, g . The chamber e is 60 provided with a port, h , by means of which the water from the supply-pipe will enter the same when the port h is brought opposite the supply-passage c , while the chamber f is provided with a similar port, i , by means of which 65 the water in this chamber may pass into the discharge-passage d . (See Fig. 5.)

The valve chest I communicates with each of the annular cylinders by means of passages a and b , situated, as above described, on opposite sides of the stationary abutments C. When the slide-valve is in a certain position the passages a and b communicate, respectively, with the chambers e and f in the slide-valve through 70 openings k and l , formed in the shell of the latter, as best seen in Fig. 1.

In the drawings the position of the slide-valve in relation to the other parts is such as to admit the water from the supply-passage c into the chamber e in the valve, and then 80 through one of the openings k , through the passage a , into one of the annular cylinders between its abutment C and its piston E, as indicated by arrows in Fig. 1, thereby causing the piston-wheel D to turn in the direction of 85 the arrow 1 until the piston E strikes the abutment on the side opposite to that from which it started. While the piston is passing through the annular cylinder, as above described, the air or water in front of said piston will pass 90 out through the passage b , the chamber f , and the passage d . This motion of the piston-wheel I will call the "forward" motion.

While the piston-wheel is being rotated, as above described, by means of power applied 95 to one of the pistons only, it is necessary to provide for a free circulation of the air or water in front of the pistons in those cylinders to which power has not been admitted, and which have not been opened for the escape of air or 100 water in front of their respective pistons. This I accomplish by means of recesses m , cut across the upper face of the slide-valve in such a way as to permit communication between

the two water passages *a* and *b* when these recesses are moved opposite these passages. The relative position of these recesses and of the openings *k* and *l* in the slide-valve is such that when power is admitted to any of the cylinders by these openings the recesses *m* will come opposite to the passages leading from the cylinders not employed, and permit the air or water which may be in front of the pistons of such unemployed cylinders to circulate freely, as indicated by arrows in Fig. 4.

If my motor is attached to an elevator, the operation just described will cause the elevator to be raised to its highest position, in which position it will be held, the abutments *C* preventing any further forward movement, while the tendency to run back, caused by the weight of the elevator, will be checked by the pressure of the water in the cylinder behind the piston. If the slide-valve is now moved endwise, so that the solid portions thereof come opposite to the passages *a* and *b* and prevent the escape or circulation of the water behind the pistons, the piston-wheel and the elevator attached to it will be held in position.

When it is desired to lower the elevator, the slide-valve is again moved endwise, so that one of the recesses *m* comes opposite to each pair of passages, (designated *a* and *b*,) thereby permitting the water or air in all of the annular cylinders to circulate through the recesses *m*, leaving the piston-wheel free to follow the tendency imparted to it by the elevator, so that the latter will run down to its lower position, thereby turning the piston-wheel back to its original position, as shown in Fig. 1, the speed of the latter operation being controlled by the size of the orifice formed between the recesses *m* and the walls of the valve-chest, through which the water is allowed to circulate, and the size of these orifices being regulated by the greater or less movement of the slide-valve. It will be understood, however, that the above-described method of rotating the piston-wheel back to its normal position will not operate unless a load is attached to it, by which the desired tendency is imparted to the same.

If my motor is applied to what is termed an "overbalanced" elevator—one in which the elevator-carriage and its connections are overbalanced by a counter-weight, so that the counter-weight is heavier than the empty or partially-loaded elevator-carriage—it may sometimes be necessary to turn the piston-wheel back to its normal position by power. This I accomplish by means of two chambers, *n* and *o*, Fig. 6, formed in the end of the slide-valve opposite to the chambers *e* and *f*. The chambers *n* and *o* are provided with two openings, *r* and *s*, which can be brought opposite to the nearest pair of passages *a* and *b* by moving the slide-valve in the proper direction. In the slide-valve are formed two auxiliary ports, *p* and *q*, which, when the slide-valve is moved so that the openings *r* and *s* come under the passages *a* and *b*, will come opposite the supply and

discharge passages *c* and *d*. (See Fig. 6.) The water entering through the passage *c* will pass into the chamber *n*, then through its opening *r* into the passage *b*, and in front of the piston, forcing the latter back to its normal position. In the drawings I have shown only one pair of openings from the chambers *n* and *o*; but it is obvious that the chamber could be extended and a sufficient number of such openings provided to operate all the pistons shown; or the recesses *m* might be dispensed with and the piston-wheel be turned in either direction by means of power applied to the pistons.

The motor, when moving in either direction, may be stopped at any desired point by simply moving the slide-valve so that the solid portions thereof come opposite the passages *a* and *b*, thereby preventing the circulation or exit of the water in the annular cylinders and bringing the piston-wheel to a stop.

The slide-valve may be moved by the rack *t* and pinion *u*, as shown in the drawings, or in any other convenient manner.

I have shown the rope *J*, which operates the elevator, attached directly to the piston-wheel, and have provided the latter with flanges *v*, to prevent the rope from slipping off; but I do not desire to confine myself to the use of the piston-wheel for the drum, since a drum of larger size may be secured to the piston-wheel; or the drum may be mounted separately and connected to the motor by suitable gearing.

One of the objects of my invention is to secure the greatest possible economy of water in the operation of my motor. This I accomplish by proportioning the water used to the load to be applied to my motor. If the load is light, I use but one of the annular cylinders, as above described, and increase the number of cylinders so employed as the load increases; and as it is necessary to fill only those cylinders that are employed with new water, it will be obvious that much less water is used than if all the cylinders were constantly employed.

Another advantage is that the speed of the "forward" motion of the motor can be controlled by bringing more or less of the cylinders into action as more or less speed is desired, while the speed of the "return" motion of the motor, when a load is attached to it, can be controlled by regulating the size of the openings through which the water is permitted to circulate; or the return motion can be produced by means of power applied to one or more of the pistons in a manner similar to its forward motion.

Another great advantage is that after the motor has once made a forward motion the cylinders employed in causing said forward motion will always remain full of water, which will insure a steady and smooth action of the motor in either direction. This filling of the cylinders with water on both sides of the pistons occurs as follows: The normal position of the motor is, as shown in Fig. 1, with the piston against the side of the abutment *C* adjacent

to the passage *a*. As the water enters the cylinder through said passage it will cause the piston to be turned until it strikes the abutment on the side opposite to its first position, 5 where it must stop, having reached the end of its forward motion. The slide-valve is now moved so as to close up the passages *a* *b*, thereby retaining in the cylinder the water which has caused the piston to make its forward motion. Now, to permit the piston to begin its return motion, it is necessary to move the slide-valve so that the recesses *m* come opposite to the passages *a* and *b*. The water which has entered the cylinder through the 15 passage *a* will now begin to run out of the same through said passage, passing through the recess *m* and into the cylinder again through the passage *b* in front of the piston, and as the water behind the piston recedes the latter will follow it until it has reached its 20 normal position against the abutment, and the water which was behind the piston will now be in front of the same in consequence of the circulation just described. It will be understood that during this return motion the water 25 has acted on both sides of the piston during its whole motion and served to steady it, while the speed of its circulation, and consequently the speed of the piston-wheel, was 30 controlled by the size of the orifice formed between the recess *m* and the walls of the valve-chest.

When the piston begins a new forward motion, the water in front of the same, and which 35 has been used, as above described, both for the preceding forward motion and also in the return motion, will be forced out of the passage *b* into the chamber *f* of the slide-valve, and then into the discharge passage *d*, from where 40 it may run into the waste or be again used, as found most convenient.

When the drum on which the rope *J* is wound is not formed directly on the piston-wheel, it 45 may sometimes be convenient to reverse the relative positions of the cylinders and the piston-wheel—that is, the piston-wheel may be surrounded by the cylinders, and the former may rotate in the interior of the latter, as shown in Figs. 8 and 9. In these figures the 50 cylinders *B* are formed in the outer portion or shell of the motor, which is firmly secured to the ground. The piston-wheel *D*, carrying the pistons is fitted into the cylinders so as to rotate therein when the water enters either of 55 the passages *a* or *b*, which are controlled by the valve *F*, mounted on the outside of the motor. In this modification the valve-chest is dispensed with, the supply and discharge pipes being connected directly to the valve, 60 which is held in place by two guides, *a'*, projecting from the stationary position of the motor.

When the supply and discharge pipes are 65 secured directly to the valve, it is necessary that they be provided with flexible connections with the water and waste pipes. It will be understood, however, that a valve-chest

may be used and provided with stationary supply and discharge passages similar to those shown in Fig. 3.

When the motor is built in the form shown in Figs. 8 and 9, the drum on which the rope *J* is wound may be secured at one side of the piston-wheel when attached to an elevator that is not overbalanced; or, when attached to an elevator that is overbalanced, a drum may be attached to each side of the piston-wheel, one for the rope *J*, which lifts the elevator, and the other for the rope *K*, Fig. 7, which acts on the weight.

What I claim as new, and desire to secure by Letters Patent, is—

1. The combination, with a series of annular cylinders and with a piston-wheel, of a series of stationary abutments, one for each cylinder, a series of pistons firmly secured to the piston-wheel, one for each cylinder, a series of passages, *a* and *b*, arranged in pairs, each pair leading into one of the cylinders on opposite sides of its abutment, a supply-pipe and 85 a discharge-pipe common to all the cylinders, and a valve constructed to control the communication between the supply and discharge pipes and one or more of the pairs of passages *a* and *b*, substantially as described. 95

2. The combination of a series of annular non-rotating cylinders arranged side by side, a piston-wheel rotatable around the cylinders, a series of stationary abutments, one for each cylinder, a series of pistons firmly secured to the interior of the rotating piston-wheel, one for each cylinder, a series of passages, *a* and *b*, arranged in pairs, and each pair leading into one of the cylinders on opposite sides of its stationary abutment, a supply and a discharge 105 pipe common to all the cylinders, and a valve constructed to control the communication between the supply and discharge pipes and one or more of the pairs of passages, substantially as described. 110

3. The combination, with a series of annular cylinders and a piston-wheel surrounding said cylinders, of the stationary abutments *C*, the pistons *E*, firmly secured to the piston-wheel, the valve-chest *I*, the passages *a* and *b*, 115 leading from the valve-chest to the annular cylinders on opposite sides of the abutments, the valve *F*, which controls all the passages *a* and *b*, the recesses *m* in said valve, and the supply and discharge pipes, substantially as 120 set forth.

4. The combination, with a series of annular cylinders and a piston-wheel surrounding said cylinders, of the abutments *C*, the pistons *E*, firmly secured to the piston-wheel, the 125 valve-chest *I*, the passages *a* and *b*, leading from the valve-chest into the annular cylinders on opposite sides of the abutments, the slide-valve *F*, provided with a supply and a discharge chamber communicating with the 130 supply and discharge pipes and with the passages *a* and *b*, the recesses *m* in the slide-valve, and the supply and discharge pipes, substantially as described.

5. The combination, with an annular cylinder and a piston-wheel surrounding said cylinder, of a stationary abutment, C, the piston E, firmly secured to the piston-wheel, the valve-chest I, the passages *a* and *b*, leading from the valve-chest into the annular cylinder on opposite sides of the abutment, the slide-valve F, provided with a chamber, *e*, communicating with the supply-pipe and with the passage *a*,
10 a chamber, *f*, communicating with the discharge-pipe and with the passage *b* when the slide-valve is in one position, also with a chamber, *n*, communicating with the supply-pipe

and with the passage *b*, and with a chamber, *o*, communicating with the discharge-pipe 15 and with the passage *a*, when the valve is in another position, and the supply and discharge pipes, substantially as described.

In testimony whereof I have hereunto set my hand and seal in the presence of two subscribing witnesses.
